UNITED STATES PATENT OFFICE.

WALTER SCOTT DUWELIUS, OF CINCINNATI, OHIO.

PLIERS.

Application filed November 27, 1920. Serial No. 426,728.

To all whom it may concern:

Be it known that I, WALTER SCOTT DUWELIUS, a citizen of the United States, residing at Cincinnati, in the county of Hamilton, State of Ohio, have invented certain new and useful Improvements in Pliers; and I do hereby declare the following to be a full, clear, and exact description of the invention, such as will enable others skilled in the art to which it appertains to make and use the same.

The present invention relates to improvements in pliers or like gripping devices.

In order to obtain a good secure grip with a pair of pliers it is desirable that the point of contact between the edge and the pliers be of somewhat extended area. To that end it has been customary to provide special pliers with differently shaped jaws for handling special articles of irregular shape, but in a pair of pliers for general use, such for instance as part of an automobilist's kit, it is impossible to have portions of the jaw shaped for anything but the most common articles, for instance, rectangular and round objects. For articles of other shapes the ordinary pair of pliers affords an inefficient grip and may also damage the article by reason of concentration of pressure upon a single point of contact. My improved pliers are designed to overcome these objections and the principal object of the invention is to provide a pair of pliers that will satisfactorily grip and hold objects of various shapes.

Another object of the invention is to provide a pair of pliers of the above type that is simple in construction and which is rugged throughout.

A further object is to provide a pair of pliers of the above type composed chiefly of stamped parts which may be readily and cheaply assembled whereby the tool may be manufactured at but little greater cost than ordinary pliers not equipped with my improvement.

The preferred embodiment of my invention is illustrated in the accompanying drawings; in which Fig. 1 and Fig. 2 are elevations of opposite sides of a pair of pliers in accordance with my invention; Figure 3 is a side view with parts broken away of one jaw of the pliers, Figure 4 is a bottom plan view of Figure 3; Fig. 5 is a sectional view taken on line 5—5 of Fig. 1; Figs. 6 to 9, inclusive, are elevational views illustra-

tive of the manner in which my invention adapts the pliers to grip objects of various shapes.

Referring to the drawings, the numerals 1 and 2 indicate the plier handles and 3 shows the pin by which the two members are hinged together. The jaw 4 is rigid and is made integral with the handle 1. The fulcrum joint at 3 is strengthened by means of a plate 5 which is stamped out of sheet metal and secured to jaw 4 and handle 1 by means of rivets 6. The other jaw comprises a rigid body portion and a portion movable with respect to this rigid portion. The body member of the jaw is represented at 7 and consists of a piece of sheet metal stamped into the proper pattern, pressed into the desired shape and secured to the handle 2 by means of rivets 8. The hollow portion 9 constitutes a housing for the movable members. In this, the preferred embodiment of my invention, the movable member comprises two links 10 and 11 movable relative to the member 7 and hinged together by means of a pivot pin 12. The link 10 is pivoted to the outer end of the member 7 by means of a pin 13 about which it has a limited rotation. The link 11 is also movably connected to the jaw 7 preferably in a manner to permit both a pivotal and a sliding movement. As shown a longitudinal slot 14 is made in link 11 thereby allowing the link to be slipped over a pin 15 arranged in the member 7, when the parts are assembled. The pin 13 will then hold the jaws in place as the joint between the jaws does not allow sufficient movement for the slot 14 to clear the pin.

The faces of the links form the gripping surface and are provided with serrations as at 16 and 17 to assist in assuring a good grip.

To enhance the utility of the pliers the rigid jaw 4 is raised somewhat and flattened off at 18 to form a hammer head. The jaw 4 also carries a removable knife 19 held in place by screws 20. The knife is mainly useful for cutting wires, and the face of the jaw 4 is notched as shown to receive the wire.

The means of strengthening the fulcrum joint at 3 is shown in detail in Fig. 5. It is to be noted that the pin 3 extends through the handles 1 and 2 together with the plate 5 and the lap extension 21 of the member 7.

In Figs. 6, 7, 8 and 9 the manner in which

the jaws of the pliers adjust themselves to differently shaped articles is illustrated. The flexible mounting of the link 10 permits the link to adjust its position about 5 the rivet 13 as a center to a sufficient extent to allow a wide variation in the angle of the face of the link with respect to the face of the fixed jaw 4 so that articles with diverging faces, as shown in Fig. 6, or par- 10 allel faces as shown in Fig. 7, or converging faces as shown in Fig. 8, will all be effectively gripped by the entire surface of the link 10 and the flat face of the opposing jaw.

15 In handling curved objects as shown in Fig. 9, the jaw 11 also becomes a gripping jaw, the jaws 10 and 11 conforming to the curve of the surface by reason of their pivotal connection. It will be obvious also that 20 the jaws 10 and 11 similarly adjust themselves to engage two faces of an angular object such, for example, as an ordinary nut, thereby affording a much better grip than can be had with pliers of the present construction.

30 This specification describes in detail the preferred embodiment of my invention as is shown in the drawings. It is to be understood, however, that certain modifications of construction may be made without departing from the essential features of the invention. The exact method shown of connecting the links together and to the body of the jaw is not necessarily adhered to.

35 I claim:—

1. A pair of pliers having cooperating jaws, one of which has a flexible engaging surface adapted to shape itself to substantially the contour of the object grasped.
- 40 2. A pair of pliers having cooperating jaws, one of which comprises a body member and a plurality of sections movable with respect to each other and with respect to the body member.
- 45 3. A pair of pliers or like gripping device having two cooperating jaws, one of said jaws consisting of a body member and a series of relatively movable links.
- 50 4. A pair of pliers or similar gripping device having two cooperating jaws, one of said jaws consisting of a body member and a part movable relative to said member, the movable part comprising a series of pivotally interconnected links.
- 55 5. A pair of pliers or similar gripping de-

vice having two cooperating jaws, one of said jaws consisting of a body member and a series of pivotally interconnected links movable relative to said member, the link at one end of said series being hinged to the body of the jaw.

6. A pair of pliers or similar gripping device having two cooperating jaws, one of said jaws consisting of a body member and a series of pivotally interconnected links movable relative to said member, the link at one end of said series being hinged to the body of the jaw, and the link at the other end being slidably connected to said body member.

7. A pair of pliers or similar gripping device having two cooperating jaws, one of said jaws consisting of a body member and a series of pivotally interconnected links movable relative to said member, the link at one end of said series being hinged to the body of the jaw, and the link at the other end being provided with a longitudinal slot adapted to receive a pin secured to the body of the jaw thereby forming a slide- 75 able connection between said link and the body member.

8. A pair of pliers or similar gripping device having cooperating jaws, one of said jaws being rigid and the other consisting of a body member and a series of pivotally interconnected links movable relative to said member, the link at one end of said series being hinged to the body of the jaw near its outer end, the link at the other end being provided with a longitudinal slot adapted to receive a pin secured to the body of the jaw near its inner end, thereby forming a slideable connection between said link and the body member, said series of links 80 constituting the gripping surface of the jaw.

9. In a pair of pliers or like gripping device having two cooperating members, comprising two jaws, one of said jaws being rigid and the other consisting of a body portion and a series of links movable relative to said body portion, a fulcrum joint consisting of said two cooperating members and two strengthening plates placed together, and a pivot pin, said pin extending through the four members.

In testimony whereof I affix my signature.

WALTER SCOTT DUWELIUS.
